UNITED STATES PATENT OFFICE.

RALPH CRAFT, OF PORTLAND, OREGON.

DESIGN FOR A TIRE.

Application filed January 24, 1924. Serial No. 8,395. Term of patent 14 years.

To all whom it may concern:

Be it known that I, RALPH CRAFT, a citizen of the United States, residing at Portland, in the county of Multnomah, State of Oregon, have invented a new, original, and ornamental Design for a Tire, of which the following is a specification, reference being had to the accompanying drawing, forming a part thereof.

Figure 1 is a plan view of a tire showing my new design thereon.

Figure 2 is a section on the line 2—2 of Figure 1.

I claim:

The ornamental design for a tire, as shown.

RALPH CRAFT.
